D12-20.

OR D 13,414

EX

No. 13,414

Nov 14, 1882

UNITED STATES PATENT OFFICE.

JOHN L. POPÉ, OF CLEVELAND, OHIO.

DESIGN FOR A WEAR-IRON.

SPECIFICATION forming part of Design No. 13,414, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Wear-Irons, of which the following is a specification, reference being had to the accompanying engraving, forming part thereof.

My invention relates to a design for wear-irons for use on carriages and other vehicles; and it consists in particular features of ornamentation and configuration, which will be hereinafter more fully described, and specifically pointed out in the claims hereof.

15 The "iron" is provided with the usual ear-pieces, *a a*, perforated to receive the devices for its securement to the body or other part of the conveyance. The upper or exposed face of the iron is adorned by the presence of two 20 flat-top beads or ribs, which in the engraving accompanying the specification will be found designated by the letters *b* and *c*, respectively. The outer bead, *b*, starting from either of the lugs, runs vertically for a short distance, then 25 obliquely toward the middle of the iron, and

thence straight along the shank of the iron, while the inner bead, *c*, commencing at either lug, first runs obliquely outward, then obliquely inward toward the middle of the iron, and thence inclinedly downward until about the 30 middle of the lower edge of the shank of the iron is reached. The manner of laying out these beads, as just explained and as seen in the engraving, produces an exceedingly handsome article—not alone in so far as the feature of ornamentation is concerned, but in the shape or configuration thereof as well.

What I claim as of my invention, and desire to secure by Design Letters Patent, is—

1. A wear-iron ornamented with the flat-top 40 beads or ribs *b c*, disposed substantially as shown and described.

2. A wear-iron having substantially the form shown.

In testimony whereof I have hereunto set my hand this 22d day of June, 1882.

JOHN L. POPE.

In presence of—

CHAS. W. MOSES,
C. M. COPP.
